(57) **CLAIM**

The ornamental design for a strap, as shown.

DESCRIPTION

FIG. 1 is a front view of a strap showing our new design; FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front perspective view thereof; and,

FIG. 8 is a rear perspective view thereof.

The broken line showing is for illustrative purpose only and forms no part of the claimed design.
